INDUSTRIAL CORD TREATING APPARATUS

Robert R. Ambler, Akron, Ohio, assignor to The
B. F. Goodrich Company, New York, N. Y., a
corporation of New York

Application June 29, 1949, Serial No. 102,121

8 Claims. (Cl. 28—62)

1

This invention relates to cord treating apparatus and is especially useful in the treatment of industrial cord of rayon, cotton, nylon or other shrinkable material for use in belts or other reinforced rubber products.

In the manufacture of products of rubber-like material having cord reinforcing members it has been found desirable to coat the cords with a liquid adapted to provide increased adhesion to the rubber-like material and to dry the cord so treated.

Objects of the present invention as to provide for controlling tension of cord progressively in accordance with its condition, to provide for progressively supporting and drying the cord while reducing tension thereon in a controlled manner, to provide for reducing the tension gradually in accordance with the condition of dryness of the cord, to provide adjustment of the tension reducing support, and to provide for electrically heating the support irrespective of its adjustment.

These and other objects will appear from the following description and the accompanying drawings.

Of the drawings,

Fig. 1 is a front elevation, partly broken away and partly in section, of apparatus constructed in accordance with and embodying the invention.

Fig. 2 is a sectional view thereof, taken on line 2—2 of Fig. 1.

Fig. 3 is a cross-sectional view thereof, taken on line 3—3 of Fig. 1.

Fig. 4 is a longitudinal sectional view of the lower roller.

Fig. 5 is a cross-sectional view of the lower roller taken on line 5—5 of Fig. 4.

Fig. 6 is an axial sectional view of the upper roller.

Fig. 7 is a sectional view of the upper roller taken on line 7—7 of Fig. 6.

Referring to the drawings, the numeral 10 designates a drying cabinet which supports bearings 11, 12 in which a shaft 13 is rotatably mounted on a horizontal axis. The cabinet also supports bearings 14, 15 in which a shaft 17 is rotatably mounted parallel to and above shaft 13.

A motor 18 connected to a speed reducer 19 is mounted on a bracket 20 supported by the cabinet and drives through a sprocket 21 and chain 22 a sprocket 23 fixed to shaft 17. A conical roller 25 is also fixed to shaft 17. A second conical roller 26 is mounted below roller 25 and with its axis parallel to the axis of roller 25.

For heating roller 26 which is hollow, as seen in Figs. 4 and 5, resistance heating units 30 are

2

mounted on the inner wall of the roller and are electrically connected to collector rings 31 outside the cabinet. Brushes 32 contact the collector rings and provide for connecting the heating elements to a source of electricity. The roller 26 is heated while it rotates by current supplied thereto through the collector rings and brushes.

The upper roll 25 is also tapered in the same direction as the lower roller. It is hollow and of adjustable taper. For this purpose, it has a stationary head 35 fixed to shaft 17 and a shell 36 secured thereto at its small end and split axially from the head 35 to its large end at intervals about its circumference to provide a series of staves 37. At the open end of the shell, the free ends of the staves 37 are supported by a cone 38 axially adjustable along shaft 17.

For resiliently holding the free ends of the staves 37 against the cone 38, a coil spring ring 40 is seated in an annular groove 41 about the open end of shell 36.

For adjusting the cone 38 along the shaft, the cone is counterbored and internally threaded at its larger end, as at 42, while its small end engages a feather key 43 to prevent turning of the cone relative to the shaft. An outwardly threaded bushing 44 extends within the counterbored portion of the cone and engages the threads 42 of the cone. The bushing 44 has a radial flange 45 having spanner holes 46 for receiving a wrench for rotating it.

A collar 47 is fixed to shaft 17 adjacent flange 45. The arrangement is such that by rotating bushing 44 about shaft 17 in one direction, the cone 38 is forced into the open end of shell 36 spreading the staves 37 and increasing the taper of the cone, and by turning bushing 44 in the opposite direction, the cone 38 is retracted and taper of the roller decreased.

Provision may be made also for heating roller 25 in the manner of roll 26 and for this purpose, collector rings 50 are mounted on shaft 17 and heating elements (not shown) may be mounted on staves 37 and electrically connected thereto. Brushes 51 may be provided to supply current to the rings.

For guiding the cord, roller 25 has axially spaced apart circumferential grooves 52 to support reaches of cord in spaced apart relation and roll 26 may be similarly grooved if desired for further guiding of the cord, although this is not necessary.

The cord 60 is drawn into the cabinet and enters the first groove at the large end of the lower roller 26 and travels about the roller and to the

first groove in the large end of the upper roller 25. From there the cord passes back to the second groove of the lower roll and back and forth about the rolls in similar manner until it reaches the last groove where it travels from the cabinet. As the cord passes about the rollers the taper of the rolls permits progressive control of the condition of tension because of the reduced diameter of successive grooves. By adjustment of the taper of roller 25 the amount of tension on the cord may be nicely controlled. The adjustable feature of roller 25 provides a convenient means of accurately regulating the dimensions of the helical convolutions of the cord with respect to the particular shrinkage of the cord and further this feature is very useful where cords of different materials having different shrinkage characteristics are treated in this equipment.

Variations may be made without departing from the scope of the invention as it is defined by the following claims.

I claim:

1. Apparatus for progressively controlling the tension on industrial cord in conjunction with a heat treatment of the cord, said apparatus comprising a pair of conical rolls arranged for rotation about parallel axes, said rolls being tapered in the same direction and adapted for guiding the cord in a series of reaches about the rolls from the large ends to the small ends of the rolls, and one of said rolls having means for adjusting its taper.

2. Apparatus for progressively controlling the tension on industrial cord in conjunction with a heat treatment of the cord, said apparatus comprising a pair of parallel shafts, means fixed to said shafts and rotatable therewith having circumferential guiding grooves for cord at spaced apart intervals therealong, said guiding grooves being of progressively decreasing diameter from one end of a shaft to another and the grooves of one shaft decreasing in the same direction as the grooves of the other, means for driving one of said shafts to feed a cord about said shafts in a plurality of convolutions about both shafts from the larger grooves to the smaller grooves thereof, heating units carried by one of said shafts, and means for changing the ratio of decrease of diameter of the grooves of one of said shafts.

3. Apparatus for determinately and progressively controlling tension on industrial cord in conjunction with a heat treatment of the cord, said apparatus comprising a pair of rolls rotatable about axes extending in the same general direction for supporting and advancing a cord helically coiled about the rolls as a group, the girth about the pair of rolls at the position of initial engagement of the cord with the rolls being greater than the girth about the rolls at the position of final contact of the cord with the rolls, and one of the rolls having means for adjusting it to change the decrease in girth from the position of initial engagement of the cord to the position of final contact to permit determinate contraction of the cord.

4. Apparatus for determinately and progressively controlling tension on industrial cord in conjunction with a heat treatment of the cord, said apparatus comprising a pair of conical rolls having their surfaces converging in the same direction and rotatable about axes extending in the same general direction for supporting and advancing a cord helically coiled about the rolls as a group, the girth about the pair of rolls at the position of initial engagement of the cord

with the rolls being greater than the girth about the rolls at the position of final contact of the cord with the rolls, and at least one of said rolls having means for adjusting it to change its conical angularity to permit determinate contraction of the cord.

5. Apparatus for determinately and progressively controlling tension on industrial cord in conjunction with a heat treatment of the cord, said apparatus comprising a pair of rolls tapered throughout their lengths in the same direction and rotatable about axes extending in the same general direction for supporting and advancing a cord helically coiled about the rolls as a group, said rolls having axially spaced-apart circumferential grooves for engaging a series of helical convolutions of the cord trained about said rolls as a group, and the girth about opposite grooves of the pair of rolls decreasing progressively from the position of initial engagement of the cord with the rolls to the position of final contact of the cord with the rolls to permit contraction of the cord, one of said rolls having means for adjusting its taper to accommodate the desired contraction of the cord.

6. Apparatus for determinately and progressively controlling tension on industrial cord in conjunction with a heat treatment of the cord, said apparatus comprising a pair of rolls rotatable about axes extending in the same general direction for supporting and advancing a cord helically coiled about the rolls as a group, said rolls having axially spaced apart circumferential grooves for engaging a series of helical convolutions of the cord trained about said rolls as a group, and the girth about opposite grooves of the pair of rolls decreasing progressively from the position of initial engagement of the cord with the rolls to the position of final contact of the cord with the rolls to permit contraction of the cord, and means for adjusting at least one of the rolls to change the decrease in girth.

7. Apparatus for determinately and progressively controlling tension on industrial cord in conjunction with a heat treatment of the cord, said apparatus comprising a pair of rolls rotatable about axes extending in the same general direction for supporting and advancing a cord helically coiled about the rolls as a group, said rolls having axially spaced-apart circumferential grooves for engaging a series of helical convolutions of the cord trained about said rolls as a group, and the girth about opposite grooves of the pair of rolls decreasing progressively from the position of initial engagement of the cord with the rolls to the position of final contact of the cord with the rolls to permit contraction of the cord, means on and rotatable with at least one of said rolls for heating the roll, and the other of said rolls being tapered uniformly from end to end thereof and having means for adjusting the angle of its taper to accommodate the desired contraction of the cord.

8. Apparatus for progressively controlling the tension on industrial cord in conjunction with a heat treatment of the cord, said apparatus comprising a pair of parallel shafts, means fixed to said shafts and rotatable therewith having circumferential guiding grooves for cord at spaced-apart intervals therealong, said guiding grooves being of progressively decreasing diameter from one end of a shaft to another and the grooves of one shaft decreasing in the same direction as the grooves of the other, and means for driving one of said shafts to feed a cord about said

shafts in a plurality of convolutions about both shafts from the larger grooves to the smaller grooves thereof, one of said means fixed to a shaft comprising a plurality of adjustable staves at the grooved surface, and means for adjusting said staves to change the ratio of decreasing diameter of the grooves.
